UNITED STATES PATENT OFFICE

AUGUST MEYER, OF BERLIN-SCHONEBERG, GERMANY, ASSIGNOR TO SIEMENS-SCHUCKERTWERKE AKTIENGESELLSCHAFT, OF BERLIN-SIEMENSSTADT, GERMANY, A CORPORATION OF GERMANY

EDDY CURRENT TRACK BRAKING APPARATUS

Application filed February 27, 1933, Serial No. 658,723, and in Germany February 27, 1932.

This invention relates to marshalling or hump yards for railway vehicles in which individual cars or groups of cars are distributed and collected to form trains by causing the cars to travel under their own momentum usually along inclined tracks connected by means of switches controlled from a suitable point.

In marshalling yards of this character it is usual to provide track braking apparatus at suitable points along the tracks so as to enable the speed of travel of the cars to be controlled and determined as desired regardless of their running resistance which is generally different for different cars. During marshalling it is often required that single cars following one another along a track leading over a switch to two divergent tracks should be caused to pass on to one or other of the tracks by operating the switch between the passage of the several cars over the switch and it is obviously desirable in order to avoid delay that the distance separating the cars should be maintained approximately uniform and should not be greater than is necessary to enable the switch to be properly operated.

In order to maintain a suitable speed and spacing apart of the cars the braking apparatus must evidently be capable of rapidly and effectively reducing the speed of any car as desired and for this purpose braking apparatus of the eddy current type is particularly suitable as the braking effort exerted thereby is more rapidly built up to its full value than is the case with other types of brakes.

It will be understood however that any delay in the braking action necessarily requires that a corresponding interval between successive cars must be maintained in order to give effective control and the greater this interval the less efficiently the total trackway of the yard is utilized.

The present invention accordingly has for its object to provide means for decreasing the time interval between the initiation by the operator of the braking action of eddy current braking apparatus and the establishment of the full desired braking effort.

The invention is illustrated by way of example in the accompanying drawing of which Figures 1 and 2 are diagrammatic views of brake controlling apparatus embodying different forms of the invention.

Figure 3 being a curve diagram illustrating the operation of the apparatus of Figure 2.

Referring now first to the apparatus shown in Figure 1 it will be seen that the energizing winding 1 of the eddy current track brake is shown as supplied with rectified current from an alternating supply circuit 5 through a rectifier 3 and a transformer 4. Owing to the high self induction of the brake winding 1, the current therein only increases slowly when the electro-magnetically operated switch 6 is closed by closing the operator's control switch 2 and consequently a considerable interval of time elapses before the eddy current brake develops its full braking effort.

According to the present invention the energization of the brake winding 1 is arranged to be increased above its normal operating value when the switch 6 is first closed, this being effected by providing a choke coil 7 connected in series with the rectifier 3, and adapted to be shunted by an electro-magnetically operated switch 8, which is energized simultaneously with the switch 6 when the control switch 2 is closed.

An electro-magnetically operated control device 9 is provided, having an energizing winding connected in the circuit of the brake winding 1 and having contacts connected in the energizing circuit of the switch 8.

In operation, when the operator closes the control switch 2 in order to render the brake operative the switch 6 is closed to complete the circuit of the brake winding 1 and simultaneously the switch 8 is closed to short circuit the choke coil 7 with the result that the current traversing the brake winding 1 corresponds to the full voltage supplied from the transformer 4 through the rectifier 3. As soon as this current has attained its full working value the control device 9 opens its contacts and deenergizes the switch 8 so that the choke coil 7 is reinserted into the circuit of

the brake winding 1 and the current traversing this winding is maintained at its corresponding working value.

It will thus be seen that the voltage initially impressed upon the brake winding 1 when the switch 2 is closed is greater than the normal working value so that the current in the winding 1 rapidly builds up to its full working magnitude and the brake consequently rapidly attains its full braking effort.

Figure 2 illustrates a modified arrangement in which the development of full braking effort is accelerated differently for different degrees of braking effort.

In this case the choke coil 7 of the arrangement of Figure 1 is replaced by a number of choke coils 71, 72 and 73 connected in series with one another in the circuit of the brake winding 1. The choke coils 72 and 73 are adapted to be short-circuited by switches 82 and 83 respectively while a switch 81 is adapted to short-circuit all the choke coils 71, 72, 73 simultaneously.

The rate of increase of current in the brake winding 1 under different conditions of operation is shown in the curve diagram of Figure 3 in which the horizontal ordinates represent time and the vertical ordinates represent the current in the brake winding.

The rate of rise of this current which would occur if the invention were not utilized, is shown in dotted lines in each case.

The operator's control switch 2 shown in Figure 1 is in the arrangement of Figure 3 replaced by a controller 20 adapted to be set into one or other of three operative positions indicated at I, II and III. The control device 9 is in this arrangement provided with an energizing winding 91 connected in the circuit of the brake winding 1 and two auxiliary windings 92 and 93 the circuits of which are controlled by the controller 20.

The operation of the apparatus is as follows:

If the controller 20 is moved to the operative position I, the energizing winding of the switch 81 is supplied with current through the controller 20 and the closed contacts of the control device 9 so that the choke coils 71, 72 and 73 are short-circuited. Simultaneously the energizing winding of the switch 6 is supplied with current in series with the winding 93 and the winding 92 is also energized.

The switch 6 is thus closed and full voltage is supplied to the brake winding 1. As soon as the current traversing the winding 1 attains the value J_1 (Figure 3) the control device 9 breaks the circuit of the energizing winding of the switch 81 which thus opens and reinserts the choke coils 71, 72, 73 into the circuit of the winding 1.

When the controller 20 is moved to its operative position II, the switches 81 and 82 are initially closed and since the winding 93 is

deenergized in this position of the controller 20, the control device 9 will not be operated to deenergize the switch 81 until the current traversing the brake winding 1 has attained the higher value J_2 (Figure 3).

When the controller 20 is moved to the position III the switches 81, 82 and 83 are all initially closed and since both the windings 92 and 93 are deenergized in this position of the controller 20, the switch 81 will not again be opened until the current traversing the brake winding 1 and the winding 91 of the control device 9 attains the value J_3 (Figure 3).

The invention is evidently not limited to the particular arrangements above described and illustrated by way of example and various modifications may obviously be adopted without exceeding the scope of the invention.

Having now described my invention, what I claim as new and desire to secure by Letters Patent is:

1. The combination in eddy current braking apparatus for marshalling yards of a brake winding, means for impressing an energizing voltage upon said winding and means for automatically reducing said voltage when a predetermined braking effort is attained.

2. The combination in eddy current braking apparatus for marshalling yards of a brake winding, means for impressing a voltage upon said winding to produce a current therein and means for automatically reducing said voltage when said current attains a predetermined value.

3. The combination in eddy current braking apparatus for marshalling yards of a brake winding, means for impressing a voltage upon said winding to produce a current therein, an impedance normally connected in circuit with said winding and means for automatically short circuiting said impedance when voltage is first impressed upon said winding.

4. The combination in eddy current braking apparatus for marshalling yards of a brake winding, means for impressing a voltage upon said winding to produce a current therein, an impedance normally connected in circuit with said winding, means for automatically short-circuiting said impedance when voltage is first impressed upon said winding and means for rendering said short-circuiting means inoperative when the current in said winding attains a predetermined value.

5. The combination in eddy current braking apparatus for marshalling yards of a brake winding, an impedance connected in circuit with said winding and automatic means for rendering said impedance operative or inoperative in accordance with the current traversing said winding.

6. The combination in eddy current brak-

- ing apparatus for marshalling yards of a source of alternating current, a rectifier connected to said source, a brake winding supplied with current through said rectifier, a choke coil connected in circuit between said source and said rectifier and means for controlling said choke coil automatically in accordance with the current traversing said winding.
7. The combination in eddy current braking apparatus for marshalling yards of a brake winding, means for impressing a voltage upon said winding to cause a current therein manually controlled means for regulating said current to control the braking effort exerted and means for automatically reducing said impressed voltage when the current traversing said winding attains a value determined by said manually controlled means.
8. The combination in eddy current braking apparatus for marshalling yards of a brake winding, means for supplying energiz-

ing current to said winding, a plurality of choke coils connected in the circuit of said winding, manually controlled means for rendering said choke coils selectively operative, and automatic means for rendering all of said choke coils inoperative until the current in said winding attains a predetermined value.

9. The combination in eddy current braking apparatus for marshalling yards of a brake winding, means for supplying current to said winding, a plurality of choke coils connected in series in the circuit of said winding, manually controlled means for rendering said choke coils selectively operative, a control device for rendering all of said choke coils inoperative when a predetermined current traverses said winding and means controlled by said manually controlled means for regulating the operation of said control device.

AUGUST MEYER.
